(57) **CLAIM**

The ornamental design for a catheter package, as shown and described.

DESCRIPTION

FIG. 1 is a perspective view of a catheter package showing my new design;

FIG. 2 is a right side elevational view thereof;

FIG. 3 is a front view thereof;

FIG. 4 is a top plan view thereof;

FIG. 5 is a bottom plan view thereof;

FIG. 6 is a left side elevational view thereof; and,

FIG. 7 is a rear elevational view thereof.

The catheter shown with broken lines is not considered to be a part of the claimed design.
